UNITED STATES PATENT OFFICE.

LYMAN FARGO, OF DULUTH, MINNESOTA.

COLLAPSIBLE EGG-CASE.

1,172,779.

Specification of Letters Patent. Patented Feb. 22, 1916.

Application filed September 26, 1914. Serial No. 863,598.

To all whom it may concern:

Be it known that I, LYMAN FARGO, a citizen of the United States, and a resident of the city of Duluth, county of St. Louis, and 5 State of Minnesota, have invented certain new and useful Improvements in Collapsible Egg-Cases, of which the following is a specification.

My invention relates to collapsible egg 10 cases and has for its object the production of a device of this character through the medium of which eggs may be sent by parcel post without fear of the same being broken.

15 A further object is the production of an egg case as mentioned which will be of durable and economical construction and efficient in use.

20 Other objects will appear hereinafter. The invention consists in the combinations and arrangements of parts hereinafter described and claimed.

25 The invention will be best understood by reference to the accompanying drawings forming a part of this specification, and in which—

Figure 1 is a partially sectional top plan view of an egg case embodying my invention, Figs. 2 and 3 are sections taken on 30 lines $x-x$ and $y-y$ respectively of Fig. 1, and Fig. 4 is a view similar to Fig. 3 showing the case in collapsed condition.

The preferred form of construction as 35 illustrated in the drawings comprises a base section consisting of a rectangular bottom member 1 at the ends of which are provided upwardly extending flanges 2. Hinged at 3 to the upper edges of flanges 2 are end walls 4 and hinged at 5 to the longitudinal edges 40 of body 1 are side walls 6. The arrangement is such that, when the device is not in use, the end and side walls may be folded downwardly to position parallel with the upper side of bottom member 1 as clearly 45 shown in Fig. 4. Said end and side walls are releasably held in unfolded position by means of inwardly projecting flanges 7 which are provided at the lateral edges of 50 end walls 4, said flanges 7 being adapted for engagement with headed studs or projections 8 which project outwardly from the respective ends of side walls 6. The outer headed ends of projections 8 are adapted to engage with key hole slots 9 formed in

flanges 7, it being clear that with this arrangement, after engagement of projections 8 with said slots, inward pressure upon the end walls 4 will cause the shanks of said projections to engage with the reduced portions of said slots and thus serve to securely 55 lock the parts together. In disengaging projections 8 from said flanges it is only necessary to tilt the latter outwardly until the heads of said studs register with the enlarged portions of said slots whereupon the 60 heads of said studs will pass through said slots upon inward rocking of side walls 6.

At the open upper side of the body or base section of the case is provided a cover 10 having a depending peripheral flange 11. 70 The flange 11 externally embraces the walls 4 and 6 when the case is in unfolded condition and is adapted also to externally embrace said base section when the same is in collapsed condition as clearly shown in 75 Fig. 4.

The body may be made of cardboard, corrugated cardboard or any other suitable material as desired.

Arranged within the case are two egg- 80 engaging members between which the eggs are securely clamped when the case is in use. Each of said egg-engaging members comprises a peripheral rectangular wire frame 12 provided with a medial longitudinally extending bar 13. Upon said frame are secured two superposed flexible sheets 85 14 and 15 of durable fabric such as heavy unbleached cotton cloth, the sheet 14 being provided with spaced opening 16 adapted 90 to snugly receive eggs of a size which the case is designed to accommodate. The openings 16 are arranged in two rows at either side of bar 13, the sheet 15 being loosely secured so that when the case is in 95 use said sheet will be flexed, through engagement with the eggs, away from the sheet 14 in the manner clearly illustrated in Figs. 2 and 3. With this arrangement then it will be seen that the openings or sockets 16 serve 100 merely as means of positioning the eggs whereas the sheets 15 clampingly engage with the respective ends of the eggs to securely hold the same against relative movement. The lower egg-engaging member is 105 supported upon substantially U-shaped supporting members 17 which are swingingly mounted upon the side walls 6, said support-

ing members, when in use, being turned to project inwardly from said side walls as clearly shown in Fig. 3. When not in use, the members 17 are swung to position 5 against said side walls 6 in order to permit of inward rocking of the latter to collapsed position as shown in Fig. 4. Upon the under side of cover 10 are provided two engaging members 18 formed of wire which are swingingly secured to said cover so as to permit 10 of the same being rocked to depending or operative position or to folded position against the under side of said cover. The members 18, when in operative position, are adapted to engage against the upper egg-engaging element in order to press the latter 15 downwardly to secure engagement with the eggs. The arrangement is such that downward pressure upon the cover will simply serve to increase the pressure upon the upper egg-engaging member which will result in a more secure clamping of the eggs contained in the case. With this arrangement therefore upon securing of the cover 10 in 20 position by means of straps 19 which encircle the respective ends thereof, tightening of said straps about the case will serve simply to more securely press the upper egg-engaging element downwardly into secure 25 engagement with the eggs contained in the case. With the construction set forth it will be seen that the egg-engaging elements are positioned intermediate the top and bottom walls of said eggs but out of engagement 30 therewith so as to obviate the possibility of cracking of the shells of the eggs through contact thereof with said walls.

An egg case of the construction set forth will be found of light and economical construction and especially adapted for the 40 shipment of eggs by means of parcel post. By reason of the collapsibility of the case, the same, when empty, may be readily folded into compact form so as to occupy 45 little space for storage or shipment. In collapsing the case the side walls 6 after being unlocked from the flanges 7 are first rocked to position against the upper side of bottom 1, next the egg-engaging elements are placed 50 upon said side walls, whereupon end walls 4 are folded downwardly, and finally the cover 10 is placed over the folded base section as clearly shown in Fig. 4, the straps 19 being employed to bind the parts together.

55 While I have illustrated and described the preferred form of construction for carrying my invention into effect, this is capable of variation and modification without departing from the spirit of the invention. I, 60 therefore, do not wish to be limited to the precise details of construction set forth, but desire to avail myself of such variations and modifications as come within the scope of the appended claims.

65 Having described my invention what I

claim as new and desire to secure by Letters Patent is:

1. A collapsible egg case comprising a foldable body open at its upper side; a cover for said body; a pair of superposed coöperating egg-engaging elements loosely arranged in said body between which the eggs are adapted to be clamped; means on the side walls of said body for limiting downward movement of the lower one of said egg-engaging elements; and foldable members on the under side of said cover for pressing the upper one of said egg-engaging elements downwardly, substantially as described. 70

2. A collapsible egg case comprising a foldable body open at its upper side; a cover for said body; a pair of superposed coöperating egg-engaging elements loosely arranged in said body between which the eggs are adapted to be clamped; means on the side walls of said body for limiting downward movement of the lower one of said egg-engaging elements; and wire members swingingly mounted on the under side of said cover adapted to depend from the latter for engagement with the upper one of said egg-engaging elements to press the same downwardly, substantially as described. 80

85 3. An egg case comprising a body open at its upper side; a cover for said body; egg-engaging elements loosely arranged in said body between which the eggs are adapted to be clamped; each of said egg-engaging elements comprising a peripheral frame; a flexible covering for said frame having 90 sockets for the reception of eggs; and means for holding said egg-engaging elements intermediate the top and bottom walls of said case but out of contact therewith, substantially as described. 95

100 4. An egg case comprising a body open at its upper side; a cover for said body; egg-engaging elements loosely arranged in said body between which the eggs are adapted to be clamped, each of said egg-engaging elements comprising a peripheral frame; two superposed sheets of material secured to said frame, the adjacent sheets of said egg-engaging elements having registering perforations 105 for the reception of the respective end portions of the eggs, and the other sheets being flexible and adapted to engage with the ends of the eggs; and means for holding said egg-engaging elements intermediate the top and bottom walls of the case but out of contact 110 therewith, substantially as described. 115

120 5. An egg case comprising a body open at its upper side; a cover for said body; egg-engaging elements loosely arranged in said body between which the eggs are adapted to be clamped, each of said egg-engaging elements comprising a peripheral frame; two superposed sheets of flexible material secured to said frame, the adjacent sheets of said egg-engaging elements having register- 125 130

ing perforations for the reception of the respective end portions of the eggs; the other sheets of said elements being adapted to flex from said first mentioned sheets and engage with the ends of said eggs clamped between said elements; and means for holding said egg-engaging elements intermediate the top and bottom walls of the case but out of contact therewith, substantially as described.

6. A collapsible egg case comprising a foldable body open at its upper side; a cover for said body; a pair of superposed coöperating egg-engaging elements loosely arranged in said body between which the eggs are adapted to be clamped; hingedly mounted means on the side walls of said body for limiting downward movement of the lower one of said egg-engaging elements; and hingedly mounted means on said cover for pressing the upper one of said egg-engaging elements downwardly, said egg-engaging

elements being adapted to be inclosed in said body when the latter is collapsed, substantially as described.

7. A collapsible egg crate comprising a foldable body portion consisting of a bottom with sides and ends adapted to be folded downwardly thereon, and a cover, in combination with a resilient egg clamping and supporting device, supporting members for said device swingingly secured to said sides and a clamping element swingingly secured to the inner face of the cover and adapted to engage the egg holding device, substantially as described.

In testimony whereof I have signed my name to this specification in the presence of two subscribing witnesses.

LYMAN FARGO.
